UNITED STATES PATENT OFFICE.

LEO BRAND, OF NEW YORK, N. Y.

SMOKEHOUSE.

Application filed April 2, 1925. Serial No. 20,272.

To all whom it may concern:

Be it known that I, LEO BRAND, a citizen of the United States, and a resident of the city of New York, borough of Manhattan, in the county and State of New York, have invented a new and Improved Smokehouse, of which the following is a full, clear, and exact description.

This invention relates to smokehouses, an object of the invention being to provide within a smokehouse an improved arrangement of rotary frames into or onto which racks, trees or other devices designed for supporting meats to be smoked can be run, supported and revolved during the smoking operation.

A further object is to provide improved mounting for a rotary frame within a smokehouse and improved means for imparting rotary motion to the frame whereby the entire weight of the frame and its contents are supported either at the base of the frame or at the top of the frame or both at the base and top of the frame, but in any event the revolving means is entirely relieved of any weight of the rotary frame and its contents.

A further object is to provide a smokehouse with an improved arrangement of rotary frames therein and which is adapted for use in connection with any standard type of rack, carrier, tree, truck or other support for the meat to be smoked and which lends itself to the employment and use of standard equipment in accordance with the needs of the user.

With these and other objects in view, the invention consists in certain novel features of construction and combinations and arrangements of parts, which will be more fully hereinafter described and pointed out in the claims.

In the accompanying drawings—

Figure 1 is a view in longitudinal section, illustrating my improved smokehouse;

Figure 2 is a top plan view of the smokehouse shown in Figure 1;

Figure 3 is a view in horizontal section on the line 3—3 of Figure 1;

Figure 4 is a view in longitudinal section illustrating my invention as applied to a plurality of smokehouses located on different floors or at different levels;

Figure 5 is a view in horizontal section, on the line 5—5 of Figure 4.

1 represents the casing of my improved

smokehouse. This casing may be of any size and shape and may be constructed in various different ways. I preferably make the smokehouse of rectangular form and of sheet metal, but I, of course, do not limit myself to the particular construction of casing.

In the lower portion of the casing 1, spaced from the bottom 2 thereof, I provide a series of horizontal bars 3, which may constitute channel bars as shown, which are parallel and spaced apart and secured upon a suitable angular frame 4. These bars 3 support a circular rail or track 5.

6 represents my improved rotary frame 70 which is of general rectangular form and is supported by any desired number of wheels 7 which are mounted to rotate on the track 5. These wheels 7 may constitute caster wheels, are preferably ball bearing, and are so shaped and arranged as to reduce friction to a minimum but at the same time maintain their position on the track 5 to allow the frame 6 to be freely and easily revolved.

The frame 6 is of skeleton form and open and of a suitable width and height in accordance with the dimensions of the casing 1 to permit the frame to turn within the casing. A series of hangers 8 are secured to and depend from the top 9 of casing 1 and support a circular track or rail 10 which is preferably of the same diameter as the track 5 and parallel therewith.

On top of the rotary frame 6 a series of brackets 11 are secured, and wheels 12 are mounted in these brackets 11 and are mounted to rotate on the rail or track 10. The weight of the rotary frame 6 and its contents may be divided between the tracks 10 and 5, or either track may serve as a support and the other as a guide, in accordance with the desire of the user. It is perfectly obvious that either one of these tracks may be dispensed with, if desired, but in most cases it will be found advisable to use both.

A vertical shaft 14 projects centrally through the top of casing 1 and has a crank arm 15 thereon adapted to engage a finger 16 on the top of the rotary frame 6. It will be noted that this finger 16 is located away from the center or axis of the rotary frame and near the outer edge of the latter so that when the shaft 14 is revolved 119

the arm 15 will engage the finger 16 and impart a rotary motion to the frame.

Should it be desired to manually turn the frame, this can be done by swinging the frame first in one direction until stopped by the arm 15, and then in the opposite direction, so that whenever desired a manual manipulation or turning movement of the rotary frame is possible.

10 The shaft 14 may, of course, be driven in any desired manner but I have shown for the purpose an electric motor 17 mounted on top of the casing 1 and having a worm 18 on the shaft 19 of said motor imparting motion to a worm wheel 20 on the shaft 14.

15 The rotary frame 6 is provided at its upper portion with hangers 21 which support a straight rail 22 fixed to said hangers and located in a horizontal position as shown. This rail 22 is adapted to register with a rail 23 outside of the smokehouse so that a cage 24 if suspended from a wheeled carrier 25 may be run along the track 23 onto the track 22 and positioned inside of 20 the rotary frame 6.

25 I would have it distinctly understood that while I shall refer to the part 24 as a cage I use this term in its broadest possible sense to include any receptacle, frame or carrier on which meat or meat products can be supported or suspended during the smoking operation.

30 The casing 1 is provided with a pair of hinged doors 26 which may be opened to admit the cage or other article supporting device, and in order that the rail 23 may project into the smokehouse I provide a hinged gate or shutter 27 normally closing an opening 28 in the front of the casing 1 35 large enough to admit the carrier 25 as the latter moves from one rail to the other, as will be readily understood. To hold the cage 24 from independent accidental movement I provide removable rods 29 which may be located in any notches of parallel notched bars 30 which are secured to the frame 6, as clearly indicated in Figures 1 and 2. Also I preferably provide hooks 31 which are connected to the casing 1 and 40 which are adapted to engage eyes 32 on the frame 6 to hold the latter against turning motion while the cage or other carrier is being moved into and out of the smokehouse.

45 50 On the lower portion or bottom of the rotary frame 6 I provide channel rails 33 which may constitute a track and allow an ordinary wheeled truck to be run into the smokehouse and supported on this track within the rotary frame. In other words, I have provided not only means for moving a suspended carrier into or out of the smokehouse but also means for permitting an ordinary wheeled truck which runs on the 55 ground to be rolled into the smokehouse on

the rails 33, and supported in the rotary frame and revolved during the smoking operation.

It will thus be noted that with my improved smokehouse I make provision for the use of almost any standard equipment which may be run into the smokehouse and supported by the rotary frame and caused to turn during the smoking operation so as to smoke evenly all of the food products.

70 75 My invention is of course not limited to the manner of creating smoke within the smokehouse, but I have shown for the purpose a burner 34, and which may burn sawdust therein, in the lower portion of the smokehouse, or any other suitable means may be provided for raising the desired smoke.

80 85 In Figures 4 and 5, I illustrate my invention in a slightly modified form. The construction of each smokehouse is precisely like that above described, but I show smokehouses A and B at different levels or on different floors, and provide a drive shaft 35 similar to the shaft 14 which not only 90 drives the rotary frame 6 in the smokehouse B but also projects into the bottom of the smokehouse A and has an arm 36 thereon engaging a finger 37 on the bottom of the rotary frame 6 in the smokehouse A 95 above.

100 105 It is therefore to be noted that a series of these smokehouses on different floors may be provided and simultaneously or independently mounted. I shall also show in this modification the smokehouse B as sunk within a pit having a passage chamber 38 outside of the smokehouse with a grating 39 over the same and hinged rail sections 40 which may connect the rails 33 with fixed rails 41 on the ground or floor 42.

110 115 Various slight changes and alterations might be made in the general form of the parts described without departing from my invention and hence I do not limit myself to the precise details set forth but consider myself at liberty to make such slight changes and alteration as fairly fall within the spirit and scope of the appended claims.

115 I claim:

1. A smokehouse, including a casing, a circular track in the casing, and a frame in the casing having rotary movement on the track.

120 125 2. A smokehouse, including a casing, a circular track in the lower portion of the casing, wheels mounted to run on said track, and a member supported on the wheels and adapted to receive articles to be smoked.

125 130 3. A smokehouse, including a casing, fixed circular rails located at the upper and lower portions of the smokehouse, a frame, and wheels at both ends of the frame engaging the respective rails.

4. A smokehouse, including a casing, a

frame having rotary mounting in the casing, a track fixed to the frame and adapted to support a member in which meat to be smoked is carried, means for holding said

5 member against independent movement in the frame, and means for imparting rotary movement to the frame.

5. A smokehouse, including a casing, a rotary frame mounted in the casing, a track 10 secured to the frame, a fixed track outside of the smokehouse, a wheeled carrier adapted to run on the tracks and adapted to be moved into the rotary frame, a vertical shaft projecting into the center of the 15 smokehouse, a crank arm on said shaft, and a finger on the rotary frame at a point removed from the axis of the frame.

6. A smokehouse, including a casing, a rotary frame in the casing, wheels support-

ing the rotary frame, rails at the lower and 20 also at the upper portion of said frame adapted to receive wheeled carriers rolled into the casing and into the frame, and means for imparting rotary motion to the frame, said means permitting manual turning 25 of the frame in opposite directions.

7. A smokehouse, including a casing, horizontal bars secured in the casing and spaced from the bottom thereof, a circular track secured on said bars, a skeleton frame, 30 wheels at the bottom of the frame mounted to rotate on said track and supporting the rotary frame, means at the top of the frame for guiding the rotary movement thereof, and means at the top of the casing for imparting 35 rotary motion to the frame.

LEO BRAND.
